DESIGN FOR A COMBINED PERFUME BOTTLE AND STOPPER THEREFOR

Alexander Tarsaidze, New York, N. Y., assignor to Parfums Chevalier Garde, Inc., New York,
N. Y.

Application December 3, 1937, Serial No. 73,325

Term of patent 3½ years

To all whom it may concern:

Be it known that I, Alexander Tarsaidze, a citizen of the United States and resident of New York, in the county of New York and State of New York, have invented a new, original, and ornamental Design for a Combined Perfume Bottle and Stopper Therefor, of which the following is a specification, reference being had to the accompanying drawing, forming a part thereof, in which Fig. 1 is a side elevation of the combined perfume bottle and stopper therefor showing my new design; Fig. 2 is a front elevation; and Fig. 3 is a rear elevation, the stopper being removed from the bottle.

The dominant feature of my design resides in the bottle portion as shown.

I claim:

The ornamental design for a combined perfume bottle and stopper therefor, substantially as shown and described.

ALEXANDER TARSAIDZE.
